UNITED STATES PATENT OFFICE.

WILLIAM N. BOOTH, OF DETROIT, MICHIGAN.

DRIVING LUG FOR DEMOUNTABLE RIMS OF VEHICLE WHEELS.

Application filed December 5, 1919. Serial No. 342,611.

To all whom it may concern:

Be it known that I, WILLIAM N. BOOTH, a citizen of the United States of America, residing at Detroit, in the county of Wayne 5 and State of Michigan, have invented certain new and useful Improvements in Driving Lugs for Demountable Rims of Vehicle Wheels, of which the following is a specification, reference being had therein to the 10 accompanying drawings.

The invention relates to demountable rims of the type designed for mounting on fixed rims of channel cross-section, and the invention has particular reference to the construction of driving lug for transmitting the 15 torque of the wheel to the rim. Heretofore lugs for this purpose have been formed from metal stampings which were provided with rivet portions for engaging the web of the 20 channel or demountable rim, and projecting portions for engagement with the cooperating lug. To safely stand the stress, these metal stampings must be of relatively heavy gauge and it has been found in practice that 25 it is difficult to shear the metal without lateral distortion of the same. This is particularly objectionable in the forming of the rivet portions of the lug as it interferes with a proper fit in the aperture in the web. 30 To overcome this defect I have devised a method of forming the lug which consists essentially in first blanking from sheet metal of thinner gauge and then folding the blank to obtain the required thickness. Thus the 35 lighter gauge facilitates the shearing operation without distortion and by folding the blank so that the opposite sides of the lug are formed from portions originally on the same side of the blank practically all distortion is eliminated. 40

In the drawings:

Figure 1 is a plan view of the blank;

Figure 2 is a cross-section thereof after the preliminary folding operation;

45 Figure 3 is a similar view of the completed structure;

Figure 4 is a longitudinal section through a portion of the rim with the lug in engagement therewith.

50 The lug in its final form is preferably of a contour forming a bifurcated portion A with a recess B between the furcations thereof and with rivet portions C and C' for engagement with apertures in the web.

55 These rivet portions are rectangular in

cross-section and are adapted to fit correspondingly shaped punch apertures in the web of the rim. It is therefore essential that these portions should be accurately formed in order that they may be easily 60 assembled and securely fastened.

As above stated, it has been found that where the lug is sheared from thick stock, the metal will be deflected laterally and will thus destroy the accuracy of form. This 65 defect I avoid by starting with stock one-half the thickness of the finished lug and blanking therefrom complementary portions D and D' on opposite sides of a center line E—E. The blank is then folded upon the 70 line E—E, first with the open return-bend, as indicated at F in Figure 2, after which the parallel side portions G and G' are pressed together, as indicated in Figure 3. Any deflection of the metal, due to the first 75 shearing operation, will be in the same direction in the double blank shown in Figure 1, but will be in opposite direction in the folded blank shown in Figure 2. Thus when the two sides of the blank are pressed 80 together, such deflection will be corrected with the result that the finished blank is accurately formed. The rivet portions C and C' will then accurately fit apertures in the web H and will be firmly secured by riveting. 85

What I claim as my invention is:

1. A driving lug for demountable rims of vehicle wheels comprising rivet portions and a projecting driving portion, both 90 formed of a folded blank.

2. A driving lug for demountable rims of vehicle wheels comprising a folded blank having complementary portions in registration with each other and forming two-ply 95 rivet portions and projecting driving portions.

3. A driving lug for demountable rims of vehicle wheels comprising a folded punched blank of sheet metal having registering portions on opposite sides which were originally on the same side, said registering portions being pressed together to mutually correct the deflections therein. 100

4. A driving lug for demountable rims of vehicle wheels comprising a folded punched blank of sheet metal having mutually correcting registering portions on opposite sides which were originally on the same side, said portions having registering 105 110

portions on their outer edges forming a rivet.

5. A driving lug for demountable rims of automobile wheels, comprising a body having a driving portion with a recess in one edge and rivet portions on the opposite edge and at opposite sides of the recess, said body comprising a folded sheet metal blank punched with corresponding projections at 10 the ends of the blank and with an aperture located centrally of the blank, said projec-

tions forming the rivet portions and said aperture forming the recess.

6. A driving lug for demountable rims of vehicle wheels comprising a body having 15 a bifurcated driving portion in one edge and rivet portions on the opposite edge, said body comprising a folded punched blank of sheet metal.

In testimony whereof I affix my signature.

WILLIAM N. BOOTH.
